UNITED STATES PATENT OFFICE.

MACK L. ROE AND JOHN T. MILLS, OF BRONSON, MICHIGAN.

BOAT-PROPELLER.

SPECIFICATION forming part of Letters Patent No. 650,613, dated May 29, 1900.

Application filed February 26, 1900. Serial No. 6,568. (No model.)

To all whom it may concern:

Be it known that we, MACK L. ROE and JOHN T. MILLS, citizens of the United States, residing at Bronson, in the county of Branch 5 and State of Michigan, have invented a new and useful Lighting Boat Propeller, of which the following is a specification.

The invention relates to improvements in boat-propellers.

One object of the present invention is to improve the construction of boat-propellers and to provide a simple and comparatively-inexpensive one adapted to be readily applied to an ordinary row-boat and capable of ready adjustment to enable the paddle-blades 15 to be readily set for striking the water properly whether the boat be lightly or heavily loaded.

A further object of the invention is to enable the paddle-blades at opposite sides of the boat to be operated independently of each other, so that the boat may be guided by the propelling mechanism without the use of a rudder.

The invention consists in the construction and novel combination and arrangement of parts hereinafter fully described, illustrated in the accompanying drawings, and pointed out in the claims hereto appended.

In the drawings, Figure 1 is a perspective view of a boat provided with propelling mechanism constructed in accordance with this invention. Fig. 2 is a longitudinal sectional view of the driving mechanism. Fig. 3 is a vertical horizontal sectional view of the propelling mechanism of one side of the boat on the line 3 3 of Fig. 2. Fig. 4 is a detail sectional view on line 4 4 of Fig. 2. Fig. 5 is a sectional view on line 5 5 of Fig. 1.

Like numerals of reference designate corresponding parts in all the figures of the drawings.

1 1 designate vertically-adjustable standards mounted on the exterior of a boat 2, at 45 opposite sides thereof, and provided with upper and lower adjustable bearing-boxes 3 and 4, receiving upper shafts 5 and lower shafts 6. The upper shafts are provided with crank-handles 7 and carry sprocket-wheels 8, which 50 are connected by sprocket-chains 9 with lower sprocket-pinion 10. The lower sprocket-pinion 10 are keyed or otherwise secured to

the inner ends of the lower shaft 6, which extend outward through bearings of rectangular frames 11, forming guards for paddle-blades 12 and supporting the lower shafts. 55

The frames 11, which are located at the outer faces of the standards, are arranged substantially in a horizontal position and are supported by guy-rods 13 and 14, extending 60 forward and rearward at the ends of the frames, at the outer sides thereof, and connected with the sides of the boat, near the bow and stern, as clearly shown in Fig. 1. The guy-rods 13 and 14 are composed of sections connected at their inner ends by turnbuckles 15, adapted to adjust the said guy-rods, whereby the rectangular frames 11 are properly supported. 65

The vertical standards are supported in an 70 upright position by front and rear inclined guy-rods 16 and 17, connected with the standards at the upper ends thereof and with the front and rear portions of the frames at the inner sides thereof, as clearly shown in Fig. 75 1 of the drawings.

In order to enable the paddle-blades to be readily adjusted to operate on the water properly when the boat is lightly or heavily loaded, the standards are adapted to be raised and 80 lowered and are secured between their ends adjacent to their centers to the sides of the boat by clamps 19 and are provided with longitudinal openings 20, which may be formed in any suitable manner. The clamps 19, which 85 are mounted upon the boat, extend through the slots or openings 20 of the standard, and are provided with nuts or other suitable clamping devices whereby the standards are held at any desired vertical adjustment. The guy-rods 90 are preferably movably secured to the sides of the boat by this construction, and by means of their turnbuckles they may be readily adjusted to support the standards firmly in their adjusted position. 95

The paddle-blades, which are clipped or otherwise secured to the lower shaft, are preferably pointed, as shown, to enable them to enter the water readily and leave the water with the least resistance. When the crank-handles of the upper shafts are rotated, motion will be communicated to the lower shafts and the boat will be driven through the water, as will be readily apparent. The pro- 100

pelling devices of the opposite sides of the boat are adapted to be operated independently of each other, and by this means the boat may be guided without a rudder.

5 It will be seen that the boat-propeller is exceedingly simple and inexpensive in construction, that it is easily operated, and that the paddles may be adjusted vertically to suit the position of the boat in the water, so that they 10 will strike the latter properly and operate to the greatest advantage.

What we claim is—

1. In a propeller for boats, the combination with a boat, of a standard adjustably mounted 15 thereon and adapted to be raised and lowered, said standard being located on the exterior of the boat and provided with bearings, shafts journaled in the bearings, one of the shafts being extended outward and located 20 at a point below the upper edges of the boat, gearing connecting the shafts, blades mounted on the extended shaft, and a frame supporting the extended shaft and receiving and forming a guard for the blades, substantially 25 as described.

2. In a propeller for boats, the combination with a boat, of a vertical standard pivotally and adjustably mounted on the exterior of the boat and adapted to be raised or lowered, 30 means for supporting the standard in its adjustment, upper and lower shafts journaled in suitable bearings of the standard, the lower shaft being located below the upper edges of the boat and extended and provided with 35 blades, gearing connecting the shafts, and means for operating the upper shaft, substantially as described.

3. In a propeller for boats, the combination with a boat, of a standard arranged at the exterior of the boat, adjustably secured to the 40 same and capable of being raised and lowered, upper and lower shafts journaled on the standard, the lower shaft being located at a point below the upper edges of the sides of the boat and extended outward and provided with 45 blades, a frame arranged at the bottom of the standard and supporting the extended portion of the lower shaft, and guy-rods connected with the frame and with the top of the standard and secured to the boat, substantially 50 as described.

4. In a propeller for boats, the combination with a boat, of a standard pivotally and adjustably secured to the exterior of the boat and adapted to be raised and lowered, upper 55 and lower shafts journaled on the standard, the lower shaft being located at a point below the upper edges of the sides of the boat and being extended outward, sprocket-gearing connecting the shafts, a frame mounted 60 on the extended portion of the lower shaft, blades secured to the lower shaft and operating within the frame, and guy-rods supporting the frame and the standards, substantially 65 as described.

In testimony that we claim the foregoing as our own we have hereto affixed our signatures in the presence of two witnesses.

MACK L. ROE.
JOHN T. MILLS.
